UNITED STATES PATENT OFFICE.

JOHN A. STEVENS, OF LOWELL, MASSACHUSETTS.

STEAM-BOILER.

SPECIFICATION forming part of Letters Patent No. 660,660, dated October 30, 1900.

Application filed January 31, 1900. Serial No. 3,406. (No model.)

To all whom it may concern:

Be it known that I, JOHN A. STEVENS, residing at Lowell, in the county of Middlesex and State of Massachusetts, have invented new and useful Improvements in Steam-Boilers, of which the following is a specification.

These improvements relate to tubular steam-boilers having superheating attachments and furnaces therefor.

10 An object of my invention is to provide a system of baffling so arranged that the passages through which the heated products of combustion travel on their way from the furnace to the stack are gradually reduced in order that as their volume decreases, owing 15 to the decrease of temperature, their distribution over the area of heating-surfaces in such passages will be equalized.

15 A further object of my invention is to arrange the baffles and direct the heated products of combustion so as to avoid short-circuiting or cutting out of the track of the heated gases portions of the heating-surfaces.

20 A further object of my invention is to provide an improved form and arrangement of superheater adapted to be either used or disconnected from the system.

25 Other advantages resulting from my improvements will appear from the following 30 detailed description.

In the accompanying drawings, Figure 1 is a longitudinal sectional view of a boiler, illustrating my improvements, taken on the line *a a* of Fig. 2. Fig. 2 is a transverse sectional view thereof, taken on the line *b b* of Fig. 1. Fig. 3 is a transverse partial sectional view taken on the line of the fire and ash doors of the grate-chambers. Fig. 4 illustrates a modified form of superheating apparatus 35 which may be employed. Fig. 5 is a plan view of the superheater-drum and its connections. Fig. 6 is a view illustrating the connection between the water-boxes in the division-wall and the steam-and-water drum. Fig. 7 is a sectional view of a preferred form 40 of cap for the headers.

45 In the drawings the primary passes or combustion-chambers 1 1' are separated by a division-wall 2, comprising in its construction water-boxes 3 and refractory tiles or bricks 4, which extend upward from the hollow base

5 to the roof-baffle 6, the division-wall separating the grates 7 7' and their respective combustion-chambers. The respective grates and grate-chambers or primary passes extend 55 from this division-wall to the containing-walls 8 8', which inclose the water-boxes 9 9' and the refractory tiles or bricks 10 10', supported upon the hollow bases 11 11'. The refractory tiles 12 12' are used to reduce the 60 grate area either in one combustion-chamber or both when the boiler is operated for maximum economy, and are taken out and the fire spread over the whole grate area when the maximum power of the generator is demanded. In case of forced draft the channels or air-ducts 5, 11, and 11', connected with the space beneath the grate, as by the openings 41, are employed for conducting the blast thereto.

70 The water-box headers 13 13' connect the respective ends of the water-boxes 3 and are connected by the tubes 14 14' with the steam-and-water drum 15 and the horizontal water-box 16, respectively, the drum 15 and the water-box 16 being connected by the tubes 17, which support the roof-baffle 6. A blow-off pipe 13" is connected with the header 13. The water-boxes 9 9' are connected with the steam-and-water drum 15 and the horizontal 75 water-box 16 by the end headers 19 19'. The steam-generating tubes 18 18' have their respective ends connected by the sectional headers 19 19'. The headers 19 are connected directly with the drum 15 and are provided at their bases with the studs 20, which are received by the apertured supporting-plate 21. A mud-drum 39, located above the fire-doors 41, is connected to the front headers by the nipples 38. The headers 19' are 80 connected directly with the water-box 16 and are supported upon the chairs or struts 22 and are free to slide upon the plates 23 in compensating for expansion or contraction. The struts 22 also sustain the refractory wall 95 24 at the rear of the primary combustion-chambers.

85 The horizontal baffles 25 25' and the diagonal baffles 26 26' of the primary pass or combustion-chamber are sustained by the tubes 18 18'. The diagonal baffles 27 27' of the secondary passes and the horizontal baffles 28

28' of the tertiary passes are sustained in like manner. The arrangement of these baffles is such that the heated products of combustion are always carried in directions trans- 5 verse to the steam-generating tubes through constantly-contracting passages so disposed as to afford easy circulation for the gases and avoiding short-circuiting.

In the upper region of the primary and secondary passes are placed tubes 29 29', preferably coiled, as illustrated in Fig. 2, which connect the steam-and-water drum 15 with the superheater-drum 30. The superheating-tubes are made in separable parts and joined 15 by a coupling 29" in order that the part beneath the roof-baffle, subjected to great heat, may be removed and renewed. The superheater-drum communicates with the steam-and-water drum through the valved flooding 20 connections 31 31', which are left open until steam rises and fills the superheating-tubes, when they are closed. Steam is drawn off from the superheater-drum by means of the "take-off" 32 and water by means of the 25 valved drain-pipe 33. The steam-and-water drum is provided with a steam - baffle 34, closed at both ends, affording communication between the steam-space of the steam-and-water drum and the tubes 29 through the 30 aperture 35 at the top of the drum. The steam-and-water drum is also provided with the dry-pipe 36 and the take-off 37, which may be used for taking off steam when the superheater is omitted or for a safety-valve mounting 35 when the superheater is used.

In the construction of the caps 42 for the headers the cap proper, 43, fitted with the joints 44 and 45, which receive annular ring-packings, is held to the opening 46 through 40 the header by a bolt 47, which passes through the washer 48 and is drawn up by the hooded nut 49.

In operating the boiler water is admitted by the feed-pipe 15' to the steam-and-water 45 drum 15, whence it flows through the water-circulating and steam-generating system by way of the downcomers or headers connected therewith. As steam collects in the upper half of this drum it is compelled to travel to 50 the extreme top thereof in order to escape above the steam-baffle 34 to the superheating-tubes 29 29', through which it passes to the superheater-drum 30, whence it is drawn off. As the passage of the steam through the su- 55 perheating-tubes carries it through a very hot part of the combustion-chambers, where it has greater or less "dwell," particularly in the construction of tubes illustrated in Fig. 2, the steam taken from the superheater- 60 drum is in a highly dry and superheated condition.

The arrangement of the baffles for the grate-chamber and primary pass enables the grate to be extended beneath all of the passes of 65 the combustion-chamber of each division of the furnace, affording a very large grate area as compared with the space taken up. By

using the diagonal spaces between the tubes for sustaining the diagonal baffles economical supports are provided, and the arrangement of the baffles effects the concentration of the heated products of combustion and provides an easy course for conducting the gases into active contact with the gradually-contracting area of heating-surface as they pass from the 75 primary combustion-chambers between the primary baffles and the secondary baffles and between the secondary and tertiary baffles to the funnel.

The ability to use either one or both compartments of the furnace to adjust the grate area or areas, to adjust the baffles supported by the water-circulating and steam-generating tubes, and to remove the superheating-tubes renders the regulation and repair of the 85 boiler and furnace advantageous in a marked degree.

Having thus described my invention, I claim—

1. In a steam-boiler, a steam-and-water 90 drum, a superheater-drum, a series of superheating-tubes connecting said drums, and a valved flooding-pipe connecting said drums, substantially as specified.

2. In a steam-boiler, a steam-and-water 95 drum, a superheater-drum substantially parallel thereto, a series of sectional superheating-tubes connecting said drums, and a valved flooding-pipe connecting said drums, substantially as specified.

3. In a steam-boiler, a steam-and-water 100 drum, a superheater-drum, a series of superheating-tubes leading from said steam-and-water drum to said superheater-drum, and a baffle for compelling steam to travel to the 105 top of said steam-and-water drum in passing to said superheating-tubes.

4. In a steam-boiler, a combustion-chamber, a roof-baffle therefor, a steam-and-water 110 drum, a superheater-drum, and superheating-tubes passing through said roof-baffle and leading from said steam-and-water drum to said superheater-drum.

5. In a steam-boiler, a combustion-chamber, a roof-baffle therefor, a steam-and-water 115 drum, a superheater-drum, a series of superheating-tubes passing through said roof-baffle and connecting said drums, a valved flooding-pipe connecting said drums, and a valved drain-pipe leading from said superheater- 120 drum.

6. In a steam-boiler, a combustion-chamber, a roof-baffle therefor, a steam-and-water 125 drum, a superheater-drum, and superheating-tubes connecting said drums, said tubes extending above and below said roof-baffle and having coils in said combustion-chamber.

7. In a steam-boiler, a combustion-chamber, a roof-baffle therefor, inclined baffles for said combustion-chamber, a steam-and-water 130 drum, a superheater-drum, and superheating-tubes connecting said drums, said tubes passing through said combustion-chamber and said baffles concentrating the gaseous prod-

ucts of combustion and directing the same transversely to said tubes, substantially as specified.

8. In a steam-boiler, a pair of combustion-chambers, a roof-baffle therefor, inclined baffles in each of said combustion-chambers for concentrating and directing the fuel products in passing therethrough, and superheating-tubes passing through each of said combustion-chambers, said baffles concentrating the

gaseous products of combustion and directing the same transversely to said tubes, substantially as specified.

In testimony whereof I have hereunto set my hand, in the presence of the subscribing ¹⁵ witnesses, this 27th day of January, 1900.

JOHN A. STEVENS.
